PORTABLE LAMP GUARD

Rudolf Popp, Valparaiso, Ind., assignor to McGill
Manufacturing Company, Inc., Valparaiso, Ind.,
a corporation of Indiana

Application September 24, 1943, Serial No. 503,595

9 Claims. (Cl. 240—54)

1

The present invention relates to guards for portable lamps and more particularly to an improved insulating type of guard which is detachable from a socket carrying handle in which the lamp receiving socket is mounted, and to improved methods of making the guard.

Guards have long been employed for insulating portable lamps against envelope and filament breakage during handling, and the usual device of this character conventionally comprises a plurality of metal parts which are interconnected to form a cage within which the lamp bulb is disposed. Portable lamp guards employing parts formed primarily of insulating material have also been manufactured for use in applications where electrical short circuits through the parts of the guard are to be avoided. Guards employing parts formed of insulating material and combined with portable lamps of the so-called vapor sealed type, have also been manufactured for use in areas where static discharges or arcs between the parts of the guard and other metal objects are to be avoided, due to the presence of inflammable and explosive gases. The latter type of guard, however, universally employs metal parts, such, for example, as eyelets, nuts or rivets, for the purpose of joining the parts formed of insulating material, and frequently machine screw or other expensive cutting operations are resorted to in order to prepare the parts for assembly. These expedients are expensive, both from the standpoint of material cost and from the standpoint of the number of assembly operations required to manufacture a completed device. Devices utilizing such fastening expedients are, moreover, highly susceptible to breakage during the handling which accompanies the use thereof, due to the fact that the component insulating parts are necessarily weakened in cutting the same to accommodate the metal fastening parts. Moreover, the arrangements presently in use for sealing the bulb within an enclosure to prevent gas ignition in cases of bulb breakage, are relatively complicated and expensive to manufacture.

It is an object of the present invention, therefore, to provide an improved portable lamp and guard structure which is substantially free of the disadvantages outlined above and may, without manufacturing changes, be readily adapted for use as a non-vapor sealed lamp or as a vapor sealed lamp.

It is another object of the present invention, therefore, to provide a portable sealed lamp which includes improved facilities for enclosing the lamp

2

bulb within a sealed space and for guarding the bulb and enclosing transparent sealing wall against breakage.

It is another object of the invention to provide an improved portable lamp guard of the character described which consists solely of interfitting parts formed of fibrous insulating material and in which the parts are held together solely by the engagement of the interfitting portions thereof.

It is still another object of the invention to provide as a part of the improved all fiber lamp guard structure, a fibrous light reflecting element which may easily be assembled with the other parts of the structure and is rigidly secured to the guard structure without the use of any metal parts.

According to a further object of the invention, there is provided an improved structure of the character described which is so arranged that no metal assembly parts are required in the assembly of the device and no expensive machine tool operations are required in order to prepare the parts for assembly.

According to still another object of the invention, all parts of the improved structure are coated with a waterproofing substance which also acts to insulate the structure against physical shock and to enhance the rigidity of the joints formed between the interfitting parts of the structure.

It is a further object of the invention to provide an improved structure of the character described which is so arranged that all parts of the structure may be stamped out on a production basis without special machine tool operations on the individual parts.

More generally stated, it is an object of the present invention to provide an improved structure of the character described which may be simply and easily manufactured with a minimum number of simple cutting and assembly operations, employs easily obtainable and cheap material, and yet is of rugged and light-weight structure.

It is still another object of the invention to provide an improved and simple method of making lamp guards from parts which consist solely of insulating material.

It is a still further object of the invention to provide an improved and simple structure for obtaining a sealed connection between the transparent bulb enclosure and the handle within which the bulb receiving socket is mounted.

The invention, both as to its organization and

method of assembly, together with further objects and advantages thereof, will best be understood by reference to the following specification taken in connection with the accompanying drawings, in which:

Fig. 1 is a side view of a portable lamp holder having combined therewith a lamp guard structure characterized by the features of the present invention;

Fig. 2 is a top view of the lamp guard structure shown in Fig. 1;

Fig. 3 is a side view of one of the side members embodied in the improved lamp guard structure;

Fig. 4 is a bottom view of the base ring embodied in the lamp guard structure;

Fig. 5 is a top view of one of the assembly rings embodied in the lamp guard structure;

Fig. 6 is a top view of the bracing ring embodied in the structure;

Fig. 7 is a perspective view, partially in section, illustrating the mode of assembly of certain of the parts included in the structure;

Fig. 8 is a sectional view taken along the lines 8—8 of Fig. 7 illustrating the manner in which one of the side members is joined to the two assembly rings provided in the structure;

Fig. 9 is a side view partially in section illustrating a modified embodiment of the guard structure having an improved reflector arrangement incorporated therein;

Fig. 10 is a sectional view taken along the lines 10—10 of Fig. 9;

Fig. 11 is a side sectional view illustrating another embodiment of the combined guard and reflector structure;

Fig. 12 is an end sectional view of the structure shown in Fig. 11;

Fig. 13 is a side view partially in section illustrating a portable lamp holder and guard identical with that shown in Fig. 1 but provided with improved facilities for enclosing the bulb within a sealed chamber;

Fig. 14 is a top sectional view of the holder shown in Fig. 13; and

Fig. 15 is a fragmentary sectional view of a modified structure for providing a sealed connection between the bulb enclosing globe and the handle of the holder shown in Fig. 13.

Referring now to the drawings and more particularly to Figs. 1 and 2 thereof, the portable lamp holder there illustrated comprises a handle 10 which is formed of insulating material, such as molded Bakelite or the like, and is provided at its upper end with a flared portion 10a suitably apertured to receive and have rigidly mounted therein a standard incandescent lamp socket. Integrally formed radially extending ribs 13 are provided around the circumferential surface of the handle portion 10a, which are drilled and counterbored to receive assembly screws 14 in a manner such that the heads of the screws are not exposed. The handle 10 is also provided with an axially disposed bore for receiving the conductors of a cord 11, these conductors being connected in the customary manner to the terminals of the lamp socket mounted within the enlarged apertured portion 10a of the handle. At its lower end the handle 10 is counterbored and tapped to receive the external threads of an anchor cap 12, which is also formed of insulating material. As best shown in Fig. 13 of the drawings, this cap is drilled to provide an opening 12a of slightly greater diameter than the cord 11, and is then counterbored through the threaded end thereof to provide an annular space 12b surrounding a

section of the cord. Adjacent the upper end of the cap, the handle 10 is provided with a transversely extending portion 10c having an opening 10d therethrough which is of the same diameter as the opening 12a. A soft rubber sleeve 8 is disposed within the annular space 12b and is of greater length than this space, so that as the cap 12 is threaded into the tapped end of the handle 10 the end portions of the sleeve are extruded within the spaces between the cord 11 and the walls of the two openings 12a and 10d, and the intermediate sections of the sleeve are swelled against the conductor 11 and the sides of the bore 12b. Thus, the cord 11 is fixedly anchored within the cap 12 and a hermetic seal is provided for preventing gases or liquids from entering the hollow portion 10b of the handle through the cord opening.

At the upper side thereof, the flared portion 10a of the handle 10 is provided with a flat, platform-like surface upon which the improved lamp guard is rigidly mounted. Briefly considered, this guard comprises a base plate in the form of an annular ring 15, eight side members 16, a bracing ring 17, a pair of assembly plates in the form of annular rings 18 and 19, a suspension hook 20 and a hook securing device in the form of a rawhide strip 21. All of the enumerated parts are formed of hard insulating material and, preferably, are constructed of a hard fibrous material such as compressed fibre. As will be apparent from a consideration of the detail views thereof, each of the enumerated parts is formed of flat stock such that they may be stamped out in production quantities by utilizing stamping dies of appropriate design. Moreover, each part is of such configuration that all required cuts may be performed with a single stamping operation. Thus, expensive machining operations and repeated cutting operations on single elements of the structure are completely eliminated.

More specifically to consider the structural arrangement of the component parts of the guard, it is pointed out that the base ring 15 is provided around the surface thereof with eight equiangularly spaced-apart recesses or openings 22 which are substantially square and extend transversely through the thickness of the ring. At the lower side of the ring 15, the opposed side walls of each opening 22 are beveled or flared outwardly in the manner indicated at 22a in Fig. 4 of the drawings, for the purpose of joining the ring with the side members 16 in the manner described below. The base ring 15 is also provided with four angularly spaced-apart openings 23 through the thickness thereof, which register with the openings through the ribs 13 of the handle 10, and are tapped or threaded to receive the threaded ends of the assembly screws 14 for the purpose of rigidly mounting the guard upon the upper flat surface of the handle 10.

Each of the side members 16 is of the configuration illustrated in Fig. 3 of the drawings. As there shown, each side member is provided with a notched lower end 16a and with an eared upper end 16b, the two ends being joined by a straight section 16c and a curved section 16d. Each side member is further provided with a notch 16e at the point along the length thereof where the curved section 16d merges with the straight section 16c. More specifically, the notched lower end of the illustrated side member 16 is provided with a portion 16f of reduced width and substantially square cross section which is adapted to tightly fit within and to extend through any

one of the openings 22 provided in the base ring 15, so that the shoulders extending outwardly therefrom engage the upper surface of the base ring. The upper extremity of the illustrated side member 16 is provided with two oppositely extending ears 16g and 16h which are of square cross section and are respectively arranged to be inserted through openings provided in the assembly rings 18 and 19 in the manner more fully pointed out below.

The assembly washers or rings 18 and 19 are of identical structure, each thereof being provided with eight equiangularly spaced-apart openings 24 which extend transversely through the thickness thereof, are substantially square, and are of such dimensions as to tightly engage the ears 16g and 16h of the side members 16. As best shown in Figs. 5, 7 and 8, the side walls which define each opening 24 through the ring 18 are provided with beveled or outwardly flared portions 24a on one side of the ring for the purpose of anchoring an ear 16g inserted therethrough in the manner explained below. Similarly, the opposite side walls of each opening through the lower assembly ring 19 are beveled or flared outwardly at the lower side of this ring so that an ear 16h of one of the side members 16 may be anchored therewithin. The two assembly rings 18 and 19 are provided with centrally aligned openings which receive an end 20a of the suspension hook 20, this end of the hook being of reduced width such that shoulders are provided for bearing against the upper surface of the upper assembly ring 18. The portion of the hook end 20a which extends through the aligned openings of the assembly rings 18 and 19 is drilled at a point therealong adjacent the undersurface of the ring 19 in order to receive the rawhide strip 21 and thus retain the hook 20 supported upon the two assembly rings.

As best shown in Fig. 6 of the drawings, the annular bearing ring 17 is of the same sectional width as the side members 16 and is provided with each equiangularly spaced-apart notches 17a which extend radially outward from the inner circumferential surfaces thereof and are of such width as tightly to embrace the side surfaces of the side members 16 when interfitting with the notches 16e of these side members. In this regard it is also pointed out that the width of the notch 16e formed in each side member 16 is such that the upper and lower surfaces of the notch will tightly embrace the adjacent upper and lower surfaces of the bearing ring 17 when the notched portions of the bearing ring and side member are brought into interfitting engagement.

In the assembly of the improved guard, the base ring 15 is supported upon a suitable holding fixture and the end 16f of the eight side members 16 are inserted through the eight openings 22 of the base ring so that the extreme end portions thereof project slightly beyond the lower surface of the base ring. It will be understood that in this assembly operation, the ends 16f are so inserted within the openings 22 of the base ring that the upper or offset ends 16b thereof converge at their extremities. The portions of the side member ends 16f which project outwardly from the lower surface of the base ring 15 are now upset or spread by a suitable press or peening operation, either individually or collectively, depending upon the machinery available. During the upsetting operation, that portion of each end 16f which projects beyond the lower surface of the bearing ring 15 is spread

or mashed to be accommodated by the beveled portions of the openings 22. In other words, during the upsetting operation, flange-like portions of the side member ends 16f are produced, which overlie the beveled surfaces 22a of the opposed side walls in each opening 22. In this regard it is noted that the amount of material of each side member end portion 16f which projects below the lower surface of the base ring 15 is just sufficient to fill the beveled portions of an opening 22 when expanded during the upsetting operation. Thus, each side member is rigidly anchored to the base ring 15 with the lower end surface thereof exactly flush with the lower surface of the bearing ring.

Either before or after the upsetting operation is completed in the manner just described, and preferably before, the bracing ring 17 is so positioned that the slots 17a therein angularly coincide with the upstanding side members 16. The bracing ring is now telescoped down over the side members 16 with the slots 17a embracing the side surfaces of the side members until it is horizontally aligned with the slots 16e provided in the side members. As the slots 16e are thus brought into alignment with the bracing ring 17, the side members snap outwardly so that each portion of the bracing ring disposed opposite a slot 17a is embraced by the side walls of a slot 16e and each portion of each side member disposed opposite a slot 16e is embraced by the side surfaces of a slot 17a. Thus, an interfitting dovetail connection is provided between each of the side members and the bracing ring which serves to restrain the bracing ring against movement longitudinally of the guard and to restrain the side members against relative lateral movement. In this regard it will be understood that as the bracing ring is telescoped over the side members, the side members are bent inwardly to tension the base ring 15. Accordingly, the side members 16 are snapped into interfitting relationship with the bracing ring 17 when this tension is relieved by bringing the slots 16e and 17a into adjustment.

After the base ring 15, the side members 16 and the bracing ring 17 have been assembled in the manner explained above, the upper ears 16g of the side members 16 are projected through the openings 24 provided in the upper assembly ring 18 until the lower surface of the indicated assembly ring rests upon the adjacent flat surfaces of the side members. In a similar manner, the downwardly extending ear 16h of the side members 16 are projected through the openings 24 provided in the lower assembly ring 19 until the upper surface of the ring abuts the flat under surfaces of the side members. After the rings 18 and 19 have thus been brought to bear against the upper and lower surfaces of the side member sections 16d, and occupy their final assembly positions, the projecting end portions of the ears 16g and 16h are upset or expanded to embrace the beveled surfaces 24a of the openings 24 respectively provided in the two rings 18 and 19. The amount of material of each ear 16g which projects above the upper surface of the ring 18 and the amount of material which projects below the lower surface of the ring 19 is just sufficient to fill the beveled portions of an opening 24 when expanded during the upsetting operation. Here again, the end portions of the ears 16g and 16h may be individually upset to provide the flange-like projections which overlie the beveled portions of the slots 24. On the

other hand, if suitable upsetting dies are available, the flanging of the end portions of the ears 16g and 16h may be accomplished in a single operation. As a further alternative, the assembly of all parts of the guard, with the exception of the hook 20, may be completed, after which the end portions of the projection 16f and the ears 16g and 16h may be upset in a single operation, providing suitable presses and upsetting dies are available for this purpose. Thus the assembly 5 rings and the side members are firmly anchored to each other to provide a rigid assembly of the character illustrated in Figs. 7 and 8 of the drawings.

Following the assembly of the parts 15, 16, 17, 18 and 19 in the manner explained above, all exposed surfaces thereof are covered with a coating of lacquer, varnish or other adhesive, waterproofing, cement-like material, for the purpose of closing the cells of the fibrous material from which these parts are made, and for the additional purpose of closing the interstices which may remain between the joined interfitting portions of the enumerated parts. The coating of the exposed surfaces is preferably performed by dipping the completely assembled guard in a lacquer or varnish bath in order to insure that all exposed surfaces of the component parts are completely covered. In this regard it is noted that the coating which is formed on the outer surfaces of the various parts by subjecting the assembly to a lacquer or varnish bath and then allowing the particular coating substance to set or dry, not only serves to prevent warping and disintegration of the fibrous material parts when exposed to moisture, but in addition, serves as a shock absorbing layer which prevents these parts from being bruised and weakened when subjected to blows occasioned by dropping the guard or striking the same against hard objects. Moreover, any cracks which may remain between the joined interfitting portions of the various parts are filled so that the adjacent displaced surfaces of the joints are effectively cemented together to enhance the rigidity of the structure.

The final assembly operation of the guard is that of mounting the hook 20 upon the completed cage assembly. The manner in which this is accomplished will be obvious in view of the preceding explanation. It is noted, however, that the hook is also stamped out from flat fibrous material stock and is dipped or otherwise coated with a suitable waterproofing lacquer or varnish prior to its assembly upon the cage portion of the guard. After the assembly of the guard parts has been completed in the manner just explained, the guard may be mounted upon the flared portion 18a of the handle 10 by threading the assembly screws 18 into the tapped drill holes 23 provided in the base ring 15.

Referring now more particularly to Figs. 9 and 10 of the drawings, the modified embodiment of the invention there shown, is essentially similar to that illustrated in Figs. 1 to 8, inclusive, and described above. Accordingly, like reference characters have been used to identify corresponding parts of the two structures. In the structure of Figs. 9 and 10 there is provided a thin light reflecting element 25, which is formed of a tough resilient fibrous material, such, for example, as fibre board, extends longitudinally of the guard structure, and describes an arc spanning the gaps between five of the side members 16. In order rigidly to secure the element 25 within the guard structure, the side members 16

are constructed to have straight portions 16c which extend well above the bracing ring 17 and substantially to the end of a light bulb disposed within the structure. The curved portions 16d of the side members are made somewhat flat in order to reduce the over all length of the structure, and are enlarged at the lower ends thereof so that slots 16m for receiving the end edge of the element 25 may be provided therein 10 at the ends of the straight portions 16c. Also, the portions 16c of the side members are cut to have a uniform width which is less than the width of the base ring 15, and is greater than the width of the bracing ring 17 by an amount equal to the thickness of the element 25. The excess width of each side members projects radially inward from the inner edge of the bracing ring 17 to provide a stop surface which may be engaged by a side edge of the element 25.

Aside from the structural differences just pointed out, the guard structure as shown in Figs. 9 and 10 is the same as that shown in Figs. 1 to 8, inclusive, and the elements thereof are assembled in exactly the manner explained above. The element 25, which is cut from thin flat stock 20 has a length which equals the distance between the upper flat surface of the base ring 15 and the bottom edge portions of the slots 16m. It has a width which is slightly greater than the length of the arc extending from a side surface of one of the side members 16 to the opposite side surface of the diametrically opposed side member 16, and touches the inner edge surfaces of the intervening side members 16. After assembly of the guard structure and before the parts thereof are lacquered or varnished, the reflecting element 25 may be assembled within the structure by grasping the side edges thereof and pressing these edges toward each other to deform the element into a trough-like configuration. The element may then be telescoped within the guard structure to project the upper edge portion thereof within the slots 16m of the side members 16. Coincident with the insertion of the edge portion of the element 25 within the slot 16m, the base portion of this element may be slipped over the upper surface of the base ring 15, and the side edges thereof may be slipped or forced within the side surfaces of the two diametrically opposed side members 16. Incident to the last mentioned operation, the central portion of the element 25 is brought into tight engagement with the inner edges of the three intervening side members 16. In this regard, it will be understood that the inner edge of the bracing ring 17 prevents the element 25 from bulging out through the gap between any adjacent pair of the side members.

After the element 25 has been positioned within the guard structure in the manner explained above, the inner upper edge portion of the base ring 15 may be upset at three or more points around the upper edge portion of the base ring periphery which is spanned by the element 25, thereby to provide anchoring flanges 26 in the manner indicated in Fig. 9 of the drawings. Thus the reflecting element 25 is rigidly locked against the bracing ring 17 and three of the side members 16 both along its upper and its lower edges. It is locked against rotary movement relative to the side members 16 through engagement of its side edges with the opposite side surfaces of the two diametrically opposed side members. After the reflecting element 25 has been thus anchored 50 within the guard structure, the entire assembly

may then be dipped or otherwise coated with lacquer, varnish, or another adhesive, waterproofing, cement-like material in the manner explained above. This coating not only performs the functions previously described, but in addition, serves to bond the element 25 against the bearing surfaces of the other elements of the structure, thereby to enhance the rigidity of the overall construction.

In the modified arrangement illustrated in Figs. 11 and 12 of the drawings, the side members 16 are straight throughout their length. They have a uniform width which exactly equals the width of the bracing ring 17 and is slightly less than the width of the base ring 15. The lower end assembly of the structure is exactly the same as that shown in Figs. 1, 3 and 4 of the drawings. The upper end assembly of this structure is substantially different from the corresponding end assemblies of the structures shown in Figs. 1 and 9. More specifically, the upper end assembly of the structure shown in Figs. 11 and 12 comprises a spoked wheel-like top member 27 which may be die-stamped from flat fibrous material, such, for example, as fibre board, of the proper thickness. This member is provided with an outer ring portion 27a, the inner and outer circumferential dimensions of which exactly equal the corresponding dimensions of the base ring 15. Extending radially inward from the ring portion 27a are a plurality of spokes 27b which terminate at an apertured hub portion 27c concentrically disposed within the ring portion 27a. This hub portion is provided with an aperture 27d for receiving the lower end portion of the mounting hook 20, the cotter pin 21 being provided on the underside of the hub portion 27c to span the aperture 27d and thus maintain the hook 20 assembled upon the member 27. Opposite the ends of the spokes 27b, the ring portion 27a of the member 27 is provided with rectangular apertures 27e for snugly receiving the ends 16g of the members 16 of reduced cross-section. These apertures are of the same configuration as the apertures 22, Fig. 4, provided in the base ring 15.

In the assembly of the improved guard structure, the base ring 15 is supported upon a suitable holding fixture and the ends 16f of the eight side members 16 are inserted through the eight openings of the base ring. The upper ends of the side members are then sprung inwardly to be received within the transversely extending slots of the bracing ring 17, following which the bracing ring is telescoped downwardly over the outer edge surfaces of the side members until the slots thereof are brought into coincidence with the slots in the side members. When this position of the bracing ring is established the side members snap outwardly to become interlocked with the bracing ring 17, in the manner previously explained, so that the upper ends 16g thereof are positioned to be received within the apertures 27e of the member 27. After the top member 27 is thus assembled upon the upper ends of the side members 16, the end portions 16g and 16f of the side members may be upset to provide rigid connections between all parts of the structure.

The light reflecting element 25 of the structure shown in Figs. 11 and 12 of the drawings is adapted to be held within the inner peripheral edge of the base ring 15 and the ring portion 27a of the member 27 which overhangs the side members 16 inwardly of the guard structure. The side edge portions of this element are adapted to bear against the inner edges of two diametri-

cally opposed side members 16 in the manner best illustrated in Fig. 12 of the drawings. For the purpose of maintaining this element rigidly mounted within the guard structure, it is cut inwardly at four points along each side edge thereof in order to provide tongues 25a and 25b which extend in opposite directions. During the assembly of the reflecting element within the guard structure, the tongues 25a may, by suitable finger manipulation, be pushed away from the main body of the element and positioned against the side surface of one of the side members 16 so that when released they tend to draw the edge portion of the element into tight engagement with the edge surface of the side member. Similarly, the tongues 25b may be bent outwardly away from the main body of the element 25 and so manipulated that when released they engage the side surface of the opposite side member 16 in order to draw the other side edge portion of the element 25 into engagement with the edge surface of the opposite side member. Thus the tongues 25a and 25b in their engagement with the diametrically opposed side members 16 not only serve to restrain the element 25 against rotary movement relative to the guard structure, but in addition, serve to maintain the side edge portions of the member 25 in tight engagement with the edge surfaces of two of the side members 16. The upper and lower edges of the element 25 are, of course, rigidly confined between the inner top surface of the base ring 15 and the lower surface of the top member 27. Thus a structure of great rigidity and ruggedness is provided. After the reflecting element 25 has been assembled with the other parts of the guard structure in the manner explained above, the entire structure may be dipped or otherwise coated with lacquer or varnish in the manner explained above. This coating serves to bond the reflecting element 25 to the bearing surfaces of the other parts of the guard structure, thereby further to enhance the rigidity with which the element 25 is mounted within this structure.

From the above explanation it will be understood that an improved portable lamp guard is provided, which consists solely of parts formed of hard fibrous insulating material, and that the resulting structure is rugged and is pleasing in appearance. It will also be apparent that in the manufacture of the device, no expensive machine tool operations are required. Moreover, the cutting and assembly of the component elements of the guard may be accomplished in a simple and inexpensive manner using standard equipment and with a minimum number of operations.

As best shown in Figs. 13 and 14 of the drawings, a bulb enclosing globe 30 may be utilized in conjunction with the handle and guard structure shown in Figs. 1 and 2 for the purpose of enclosing a bulb 31, with which the device is fitted, within a sealed gas tight chamber. This globe is in the form of an inverted cup, is constructed of glass having heavy wall thickness, and half the area thereof is enameled as indicated at 30a to provide a light reflecting surface. At the outer side of the rim portion thereof, the globe 30 is provided with threads 30b which are adapted for threaded engagement with internal threads 10e provided at the inner peripheral surface of the recessed end portion of the handle 10. More specifically, the enlarged upper portion 10a of the handle 10 is provided with an enlarged cup-shaped opening at which the socket receiving opening 10b terminates. Thus, a flat platform-

11

like surface 10f extending transversely of the handle 10 is provided between the walls of the enlarged cup-shaped opening and the edge socket receiving opening 10b. The inner edge of this surface is utilized to support a flange or lip 35a extending radially outward from the lamp receiving socket 35. For the purpose of providing a sealed connection between the globe 30 and the handle 10, a soft rubber washer 32 is provided, which lies flat against the surface 10f and snugly embraces the periphery of the socket flange 35a. The outer edge surface of this washer is disposed between the edge of the globe 30 and the surface 10f to be clamped therebetween when the globe 30 is threaded into the threaded portion of the handle 10. Thus, a hermetic seal is provided between the rim of the globe 30 and the handle 10. This seal, in cooperation with the seal provided by the soft rubber sleeve 8, functions to prevent inflammable gases or vapors from entering the chamber within which the bulb 31 is disposed. The bulb receiving socket 35 is held in its assembled position within the opening 10b by means of assembly elements 34 which bear against the upper surface of the flange 35a, overlie the rubber washer 32, and are held in clamping engagement with the upper edge of the socket 35 by clamping screws 33 which are threaded into the flared portion 10a of the handle 10.

The modified structure shown in Fig. 15 of the drawings is substantially similar to that just described, the principal difference being that in the Fig. 15 arrangement, the soft rubber washer 32 serves the two functions of providing a hermetic seal between the handle 10 and the globe 30 and of resiliently supporting the lamp socket 35 within the handle 10 to minimize the transmission of mechanical shock or vibration to the lamp bulb. In order to enhance the action of the rubber washer 32 in performing the last-mentioned function, this washer is provided with an upstanding annular portion 32a of greater longitudinal thickness than the remaining portions of the washer. At the upper edge thereof, the washer portion 32a supports the annular rim of the lamp socket 35 in a manner such that the side walls of the socket are displaced from the inner surface of the opening 10b within the handle 10. Assembly screws 33 and clamping elements 34, in combination with spacing columns 36, are utilized to clamp the socket rim 35a to the platform surface 10f of the handle 10 through the thickness of the annular washer portion 32a. More specifically, each spacer column 36 is in the form of a sleeve telescoped over one of the assembly screws 33 and is provided with a tapering upper surface, such that a knife edge support is provided for the associated clamping element 34 at the end thereof furthest removed from the peripheral edge of the socket flange 35a. Thus, a simple arrangement is provided by which the lamp socket 35 is resiliently supported upon the handle 10 to prevent mechanical shocks from being transmitted to a bulb or lamp supported therein.

While different embodiments of the invention have been disclosed, it will be understood that various modifications may be made therein, which are within the true spirit and scope of the invention.

I claim:

1. A portable lamp guard comprising a base, a plurality of spaced-apart side members provided with ends attached to said base and with opposite ends which converge at their extremities, said

12

opposite ends each being provided with integrally formed oppositely projecting ears which extend parallel to said side members, and a pair of assembly rings disposed on opposite sides of said opposite ends and respectively provided with spaced apertures therethrough through which said oppositely extending ears extend, said ears having flanges at their extremities which overlie segments of said assembly rings to maintain said rings and side members assembled.

2. A portable lamp guard comprising a flat base ring having spaced apertures therethrough, a plurality of side members provided with ends of reduced cross section extending through the apertures in said base and with opposite ends which converge at their extremities, said first-named ends having flanges at their extremities which overlie segments of the base ring to maintain the named parts assembled, said opposite ends each being provided with oppositely projecting ears which extend generally parallel to said side members, and a pair of assembly rings disposed on opposite side of said opposite ends and respectively provided with spaced-apart apertures therethrough through which said oppositely extending ears extend, said ears also having flanges at their extremities which overlie segments of said assembly rings to maintain said side members and assembly rings assembled together.

3. A portable lamp guard comprising a base, a plurality of side members provided with ends attached to said base and with opposite ends which converge at the extremities thereof, said opposite ends of said side members each being provided with oppositely projecting integrally formed ears at its extremity which extend generally parallel to said side members, and a pair of flat assembly rings disposed on opposite sides of said end extremities to extend transversely of said side members and respectively provided with spaced-apart apertures therethrough through which said oppositely extending ears extend, said ears being provided with flange-like portions which overlie segments of their associated assembly rings in order to maintain the named parts in assembled relationship.

4. In a portable lamp unit, the combination of a handle having a flat annular seat at one end thereof for the reception of a guard thereon, and a guard comprising a plurality of hard fibrous parts including a flat base ring with spaced-apart apertures therethrough and adapted to be mounted upon said flat annular seat of the handle, a plurality of side members each provided with an end of reduced cross-section fitting within and extending through one of said apertures so that the end surface of said side member end is substantially coplanar with the bottom surface of said flat base ring, said side-member ends having flange-like portions which overlie segments of said base ring within said apertures to retain the side members and base ring rigidly assembled together but positioned so as not to interfere with the mounting of the flat base ring on the flat annular seat of the handle, and assembly means at the opposite ends of said side members including a flat ring apertured to receive corresponding end portions of said side members extending therethrough with the outer ends of said end portions being upset to maintain said assembly means and said side members in assembled relation.

5. A portable lamp guard comprising a base, a plurality of side members provided with ends attached to said base and with opposite ends

which converge at their extremities, said side members each being provided with integrally formed oppositely extending ears at its extremity, assembly plates disposed on opposite sides of said end extremities and respectively provided with spaced-apart recesses within which said ears are anchored, said plates having aligned openings therethrough, a suspension hook having an end portion which extends through said aligned openings and is provided with a shoulder abutting the one of said plates farthest removed from said base, and means coacting with said hook end portion and the other of said plates for securing said hook to said plates.

6. A portable lamp guard consisting entirely of stamped out parts formed of hard fibrous material and comprising, in combination, a flat base ring provided with a plurality of spaced-apart apertures therethrough, a plurality of side members each provided with an end of reduced cross section fitting within and extending through one of said openings so that the end surfaces thereof are substantially co-planar with the bottom surface of said base, said notched ends being provided with flange-like portions which overlie segments of said base ring within said openings to retain said side members and base ring in assembled relationship, said side members being provided with opposite ends having integrally formed connecting portions at their extremities, a flat top member extending transversely of said side members and provided with spaced-apart openings therethrough through which said connecting portions extend, said connecting portions being provided with flange-like segments which overlie segments of said top member within said last-named openings to retain said top member and side members in assembled relationship, said side members also being provided with external notched portions at corresponding points along the lengths thereof, a continuous bracing ring adapted to be telescoped over the said opposite ends of said side members and provided with internal notched portions interfitting with the notched external portions of said side members to restrain said side members against relative lateral movement, and a waterproof and adhesive coating enveloping all exposed surfaces of all of the named parts of said guard.

7. A portable lamp guard comprising a base ring, a plurality of spaced apart side members provided with ends attached to said base ring, said side members having straight portions and curved end portions which converge at their extremities, at least a portion of said side members also being provided with inwardly disposed

notches substantially at the junctions between the straight and curved portions thereof, a top member attached to the converging extremities of said side members, a light reflecting element disposed within said side members and provided with one edge bearing against said base ring and with an opposite edge anchored within at least a portion of said notches, and means for anchoring said element along said one edge.

8. A portable lamp guard comprising a base ring, a plurality of spaced-apart side members provided with ends attached to said base ring, said side members having straight portions and curved end portions which converge at their extremities and being provided with notched portions at corresponding points intermediate the ends of said straight portions, at least a portion of said side members also being provided with inwardly disposed notches substantially at the junctions between the straight and curved portions thereof, a top member attached to the converging extremities of said side members, a bracing ring provided with notched portions interfitting with the notched portions of said side members to restrain said side members against relative lateral movement, a light reflecting element disposed within said side members and provided with one edge bearing against said base ring and with an opposite edge anchored within at least a portion of said notches, and means including a flanged portion of said base ring for anchoring said element along said one edge.

9. A portable lamp guard comprising a base ring, a plurality of spaced-apart side members provided with ends attached to said base ring, said side members having straight portions and curved end portions which converge at their extremities, at least a portion of said side members also being provided with inwardly disposed notches substantially at the junctions between the straight and curved portions thereof, the extremities of said curved end portions of said side members being provided with integrally formed oppositely projecting ears which extend generally parallel to the straight portions of said side members, a pair of assembly rings disposed upon opposite sides of said extremities and respectively provided with spaced apertures therethrough within which said oppositely extending ears are anchored, a light reflecting element disposed within said side members and provided with one edge bearing against said base ring and an opposite edge anchored within at least a portion of said notches, and means for anchoring said element along said one edge.

RUDOLF POPP.
